L. R. CARPENTER,
INTERNAL COMBUSTION ENGINE,
APPLICATION FILED FEB. 9, 1920.

1,355,452.

Patented Oct. 12, 1920.

UNITED STATES PATENT OFFICE.

LEE ROYAL CARPENTER, OF CLEVELAND, OHIO.

INTERNAL-COMBUSTION ENGINE.

1,355,452.

Specification of Letters Patent.

Patented Oct. 12, 1920.

Application filed February 9, 1920. Serial No. 357,213.

To all whom it may concern:

Be it known that I, LEE ROYAL CARPENTER, a citizen of the United States, residing at Cleveland, in the county of Cuyahoga and

5 State of Ohio, have invented a certain new and useful Improvement in Internal-Combustion Engines, of which the following is a full, clear, and exact description, reference being had to the accompanying drawings.

10 This invention relates to internal combustion engines and has for its general object the provision of a new and improved motor of the two cycle type adapted either for stationary power plants or for the propulsion 15 of vehicles either on land or water or in the air, although certain features of my invention are applicable to motors of the four cycle type, and I lay claim to my improvements in every use to which they may be

20 applicable. The objects of the invention are the provision of a motor of maximum power and of minimum weight; the provision of a motor of extremely high efficiency and low complexity; the provision of

25 new and improved two-cycle mechanism which shall be free from the disadvantages hitherto experienced in this connection; the provision of a new and improved mode of connection between the power piston and

30 crank shaft; the provision of new and improved valve mechanism for internal combustion motors; while further objects and advantages of the invention will become apparent as the description proceeds.

35 In the drawings accompanying and forming a part of this application, I have shown my improvements as embodied in a one cylinder engine, although it will be understood that great changes in detail and ar-

40 rangement can be made within the scope of my inventive idea and that my invention is applicable to multi-cylinder engines equally with single motors. In these drawings Figures 1 and 2 are central vertical sectional

45 views taken through a simple type of motor embodying my improvements; Fig. 3 is a horizontal sectional view taken on the broken line 3—3 of Fig. 2, and Figs. 4 and 5 are diagrams representing the movement of

50 the two pistons.

Describing by reference characters the parts shown in the drawing 1 represents the base, and 2 the cylinder of my improved motor, the latter being cast in a block which 55 is separated from the base along the line 3 shown in Fig. 1. The cylinder is preferably

formed with a removable head 4 and the base is formed with bearings 5—5 in which is journaled a shaft 6 formed with a crank 7 in line with the opposite end of the cylinder. Slidably mounted inside the cylinder is a double ended piston 8 traversed by a piston pin 9 which lies perpendicular to the shaft 6, the side walls of the cylinder being formed with longitudinal slots 10—10 for the passage of the same. Journaled upon the crank 7 is a bearing member 11 having laterally extending ears 12—12 which ears are connected to the ends of the piston pin by means of connecting rods 13—13 located 60 one on each side of the cylinder. The distance between the ears 12—12 being the same as the length of the piston pin, it will be seen that these connecting rods will have at all times a parallel motion. Each side of 65 the cylinder is formed with a hollow external boss 14 which extends from the line 3 to a point sufficiently near the opposite end of the cylinder to inclose the slots 10—10 which register therewith. The portion of the cylinder which projects beyond these bosses is preferably formed with cooling means, such for example as the water jacket 15. I have shown the walls of these bosses or housings as formed with removable 70 cover plates 16 by means of which access can be had to the piston pin 9 and also with removable plugs 17 through which the bearing bolts 18 can be removed if and when desired.

75 The walls of the cylinder are formed at such a distance from the removable head 4 as to be uncovered by the piston at its extreme limit of travel with opposed ports 20 and 21 respectively, while the walls of the cylinder adjacent the opposite end thereof are formed with other ports 22, 23 respectively, the port 22 however, being out of register with the port 23 and slightly nearer the middle of the cylinder. The ports 21 and 22 are connected by a transfer duct 24 formed in the cylinder wall while the port 23 communicates with a passageway 25 through which explosive mixture is supplied.

80 While it may be effected in other modes, the control of the ports 20 and 21 is preferably effected solely by the movement of the piston 8, but mechanical means of some kind is preferably employed to control either or both the ports 22 and 23. Such a 85 means is here supplied by the second piston

30 snugly mounted in the open end of the cylinder and having in its wall a port 31 adapted to register with the port 23 and communicating with the interior of the cylinder by a passageway 32. Such valve means is operated through the agency of a movable member which projects between the two connecting rods and may be actuated by suitable cams on the main shaft. In the 10 present instance the cams take the form of eccentrics 33—33, located one at each side of the crank and surrounded by eccentric straps 34 connected by a yoke 35 which bridges the crank and is articulated at 36 to the piston 30. I have found it advisable to arrange the 15 cams or eccentrics 33 in advance of the crank, in other words with a certain amount of lead; and my experience indicates that it is very desirable to employ a lead of 90°, 20 largely for the reason that in this way the action of the valve mechanism is rendered most rapid at the instant when the piston is passing dead center and consequently is moving most slowly. Also, when a piston 25 valve 30 is employed as herein shown, I arrange the same so that when in its mid-position both the ports 22 and 23 are covered and also in such wise that the port 22 is opened as that piston falls and the port 23 is opened as said piston rises from this point.

The following is a description of the operation of the particular invention herein illustrated. Starting from dead center as 35 shown in Fig. 1 the rotation of the crank in the direction of the arrow causes the working piston 8 to rise slowly while the cams 33 being in quadrature the valve piston 30 is raised rapidly with the result that the ports 40 23 and 31 are caused to register when the shaft has turned only 14° corresponding to the point as shown in Fig. 4. This permits the free entrance of explosive mixture beneath the piston 8, which rising, first closes 45 the port 21 and then the port 20 as shown at *b* and *c* in Fig. 4. The mixture in the firing chamber is compressed, new mixture being drawn in through the port 23 until the opposite dead center is approached when this 50 port is closed as shown at *d* in Fig. 4, having meanwhile been open through a shaft movement of 152°. The compressed mixture in the firing chamber being now ignited by any suitable means, the power stroke commences, and meanwhile the rapid movement 55 of the piston 30 serves to open the port 22 as shown at *e* in Fig. 4 at a point only 9° after dead center, as a result of which the fresh mixture displaced by the piston is 60 pressed into the transfer duct 24. At the point *f* shown in Fig. 4 the exhaust port 20 opens and the burned gases are discharged after having acted upon the piston through an angle of 125° 40', and at the point *g* shortly thereafter the port 21 opens permit-

ting the fresh gases to rush into the cylinder and sweep out the last vestiges of the burned gases. The port 22 does not close until the piston has almost reached the lower dead center as shown at *h* in Fig. 4.

70

As a result of this arrangement it will be seen that each of the ports is left open during the longest possible time; the incoming mixture is compressed into the duct 24 prior to the opening of the passage between that 75 duct and the working chamber, so that instantly upon the opening of those ports the inrush of the charge can begin; the ports 22 and 23 are never in communication with each other so that back firing into the carburetor is absolutely impossible; the small clearance possible between the two pistons enables the very complete transfer of gas from the compressor chamber to the firing chamber; while a minimum of difficulty is 80 experienced owing to the leakage of gas through worn bearings and the like, which has hitherto been a fruitful cause of complaint in connection with two-cycle engines.

80

It will be appreciated that the peculiar 90 connecting rod arrangement herein shown is capable of use on many other types of engines both gas and steam, two-cycle or four-cycle, wherefore I do not restrict myself to its employment with this kind of a device, 95 although it is of peculiar advantage in the combination shown; and likewise I do not restrict the valve mechanism herein shown to this type of an engine or to the combination including this particular connecting- 100 rod assembly although the two when used together offer marked advantages. It will be understood that numerous other types of valves and valve mechanism can be employed within the scope of my invention and 105 I do not restrict myself to any of the features herein shown except as specifically recited in the claims hereto annexed.

110

Having thus described my invention, what I claim is:

1. In an engine, a cylinder, piston, and crank, a crank bearing journaled on said crank and having oppositely disposed external ears arranged perpendicularly to the cylindrical axis, and a pair of twin connecting rods pivoted to said ears and to said piston.
2. In an engine, a cylinder having slotted sides, a piston in said cylinder, a piston pin traversing said piston and projecting 120 through the slots, a connecting rod articulated to each end of said pin, a crank located opposite one end of said cylinder, and a member journaled on the crank throw and having oppositely projecting ears to which 125 said rods are pivoted.
3. In an engine, a crank, a cylinder presented endwise to said crank and having slotted sides, a piston in said cylinder, a piston pin traversing said piston and projecting 130

through said slots, a bearing member journaled on said crank and having external ears, and connecting rods, one on each side of said cylinder, connected to said pin and 5 ears.

4. In an engine, a crank, a cylinder presented endwise to said crank and having slotted sides, a piston in said cylinder, a pin traversing said piston and projecting 10 through said slots, a bearing member journaled on said crank and having external ears, the distance between said ears being substantially the same as the length of said piston pin, and parallel connecting rods 15 articulated to said ears and pin.

5. In an internal combustion engine, a crank, a double-ended cylinder presented endwise to said crank and having slotted sides, a piston pin projecting through the 20 slots, connecting rods connected to said crank and to the ends of the piston pin, a crank casing surrounding said crank, and shields covering said slots and rods.

6. In an internal combustion engine, a 25 cylinder having slotted sides, a double-ended piston in the cylinder, a transverse pis-

ton pin projecting through the slots, in combination with a crank shaft perpendicular to said piston pin and connecting rods between the pin and crank. 30

7. The combination with a cylinder having longitudinally slotted walls, and a crank shaft of a piston having a pin projecting through such slots perpendicular to the crank shaft, and connecting rods articulated to said pin outside of the cylinder and connected to the crank. 35

8. In an engine a cylinder having closed ends and slotted sides, a longitudinal extending hollow boss carried by the cylinder 40 at each side and registering with one of the slots, a crank casing secured to said cylinder and bosses, a piston in said cylinder, a piston pin traversing said piston and projecting through said slots, and connecting rods, 45 one in each boss, having their outer ends articulated to said pin and their inner ends operatively connected to the crank.

In testimony whereof I hereunto affix my signature.

LEE ROYAL CARPENTER.
